UNITED STATES PATENT OFFICE.

NELSON A. MANTZ, OF AKRON, OHIO.

DRAWING IMPLEMENT.

1,107,432.

Specification of Letters Patent. Patented Aug. 18, 1914.

Application filed March 18, 1914. Serial No. 325,516.

To all whom it may concern:

Be it known that I, NELSON A. MANTZ, a citizen of the United States, residing at Akron, in the county of Summit and State of Ohio, have invented new and useful Improvements in Drawing Implements, of which the following is a specification.

This invention relates to that class of drawing implements which embodies straight edges, T-squares, and the like, and has more specific relation to T-squares.

The object of the invention is to provide a metallic T-square having a blade provided with at least one longitudinally-extending rib constituting means to receive the hollowed-out portion of a scale to guide and steady the latter during its shifting movement longitudinally of the drawing implement to hold the indicia-bearing edge of the scale approximately flush with the working edge of the implement. Besides providing a guide for the scale and interlocking means for the scale and the blade of the implement, the rib tends to stiffen and strengthen the implement so as to prevent distortion.

With the foregoing and other objects in view, the invention consists in the novel construction, combination and arrangement of parts constituting the invention to be hereinafter specifically described and illustrated in the accompanying drawing which forms a part hereof wherein is shown the preferred embodiment of the invention, but it is to be understood that changes, variations and modifications can be resorted to which come within the scope of the matter herein-after claimed.

The drawing presented is a perspective view of a drawing implement embodying this invention showing the same in connection with a triangularly-formed scale and positioned on an ordinary drawing board.

The invention contemplates the provision of some implement such for instance, as a straight-edge or a T-square of some light sheet metal, such for instance, as aluminum for the sake of cheapness, lightness, and durability, provided with one or more ribs extending longitudinally thereof.

In the drawing, the reference numeral 1 denotes the head of a T-square here used to illustrate this invention, and preferably formed of metal, and preferably provided with recessed portions 2 for the sake of lightness. Secured to the head 1 is a blade

3 held in position through the medium of hold-fast devices 4 and of a suitable or preferred length. The blade 3 is preferably formed of sheeted aluminum and is also provided with one or more upwardly-extending ribs 5 and 6 formed by upsetting the metal. One of the ribs, say for instance, 5, in the drawing, is positioned at such a point with respect to the working edge 7 of the blade of the T-square that when a scale 8 of ordinary construction and provided with a concave groove 9, is positioned thereon, the longitudinally-extending rib 5 will engage in the groove 9 of the inner face of the scale and form to a certain extent an interlocking engagement between the two, whereby the scale may be slid longitudinally and yet maintain itself at all times in a position relatively fixed transversely with respect to the working edge 7 of the blade. Under ordinary circumstances, the ribs 5 will be so positioned with respect to the working edge 7 that the indicia-bearing portion utilized by the draftsman will be approximately flush with the working edge 7, so as to be readily read by the draftsman.

It is apparent that instead of utilizing a triangularly-formed scale 8, as shown, a flat scale provided with a coöperating portion to receive the rib 5 may be employed, so long as the groove in the scale is suitably positioned as to bring the indicia-bearing portion of the scale in substantial alinement with the working edge 7.

The usefulness of the invention is apparent upon inspection, but it may be pointed out that whenever it is necessary to remove the scale for any purpose, replacement of the same in the exact position on the T-square is rendered comparatively easy and the efficiency of the draftsman is increased.

I claim:

The combination with a drawing implement such for instance as a T-square, embodying a blade formed of a strip of light sheet metal having a working edge, and provided with an integral upwardly-projecting rib on its upper face formed by bending up the metal of the blade, said rib extending longitudinally thereof and parallel with said working edge, and a scale mounted on the upper face of said blade and provided with a longitudinally-extending groove adapted to freely receive said rib, the relative position of the rib on the blade and

the groove in the scale being such that when the scale is positioned on the blade the indicia-bearing edge of the scale will be flush with the working edge of the blade, said scale being freely and bodily removable vertically from engagement with said blade.

In testimony whereof I have hereunto set

my hand in presence of two subscribing witnesses.

NELSON A. MANTZ.
